(57) **CLAIM**

The ornamental design for a jumpbox, as shown and described.

DESCRIPTION

FIG. 1 is an isometric view of the invented jumpbox showing the new design, along with connector cables, the cables being shown in dotted lines

FIG. 2 is a top view thereof;

FIG. 3 is a front view thereof;

FIG. 4 is a left end view thereof;

FIG. 5 is a right end view thereof;

FIG. 6 is a rear view thereof;

FIG. 7 is a bottom view thereof; and,

FIG. 8 is an enlarged isometric view of FIG. 1.

The broken lines shown in the drawings are included for the purpose of illustrating environmental structure and form no part of the claimed design.
